UNITED STATES PATENT OFFICE.

JOHN B. GORRELL AND HIRAM V. GORRELL, OF LAOTTO, INDIANA.

ELECTRIC SIGNAL FOR RAILWAYS.

No. 806,538.

Specification of Letters Patent.

Patented Dec. 5, 1905.

Application filed June 21, 1905. Serial No. 266,201.

To all whom it may concern:

Be it known that we, JOHN B. GORRELL and HIRAM V. GORRELL, citizens of the United States, residing at Laotto, in the county of

5 Noble, in the State of Indiana, have invented certain new and useful Improvements in Electric Signals for Railways; and we do hereby declare that the following is a full, clear, and exact description of the invention, which will 10 enable others skilled in the art to which it app pertains to make and use the same, reference being had to the accompanying drawings, which form part of this specification.

Our invention relates to improvements in 15 electric signals for railways.

The primary object of our present invention is to provide a comparatively cheap, simple, efficient, and reliable electric signal apparatus for railways, located both at stations and at 20 suitable points between stations under the exclusive control of the station operator and adapted to prevent train collisions by enabling the operator to signal trains between 25 stations at pleasure, as in case of a mistake in train orders and the like, and also by enabling the operator to simultaneously signal the office at the next station in both directions when a train leaves in the direction of such station.

Our invention consists of an electric signal- 30 ing apparatus operatively mounted in an upright casing or box adapted to be fixed upon any suitable support and placed at stations and at suitable points between the same. The operative mechanism arranged in the said cas- 35 ing consists of an electrically-operated switch adapted to be energized by a line-circuit normally open, a lamp-circuit normally open connected with the said switch, and signaling means adapted to be actuated by the closing 40 of the said normally open switch.

The principal novel feature of our invention resides in the combination of operative parts by which the station operator is enabled to signal railway-trains between stations and 45 by which the operator is notified of all approaching trains as soon as they leave the nearest station in each direction.

Similar reference-numerals indicate like parts throughout the several views, in which— 50 Figure 1 is a side view of our invention with the containing-casing or signal-box in vertical section. Fig. 2 is a front view of the same with the casing also in vertical section and showing its connection with the 55 line-batteries. Fig. 3 is a perspective view of the same in its containing-casing. Fig. 4 is

a diagrammatic view of a system employing our invention. Fig. 5 is a diagrammatic view showing the relation of the lamp and magnet circuits.

60 The casing 1, of any proper form and dimensions, in which the operative mechanism of our invention is mounted, has any suitable access to the interior, preferably by having the back 2 fixed to a proper support 2', the casing 65 being hinged at its top to this support, as shown. To the inner face of this stationary back are fixed a series of horizontal shelves 3, 4, 5, 6, and 7, respectively, for the purpose hereinafter described.

70 In the front face of the casing 1, near its upper end, is arranged an opening, preferably circular, closed by a proper transparent glass 8, fixed in a suitable frame 9. Immediately below this opening is a second smaller opening of any proper form and dimensions around 75 which is fixed a frame 10, having a proper transparent convex glass 11 fixed therein.

On the shelf 7 are arranged the batteries 80 12, having the binding-posts 13, which are connected by the wire 14. One of these batteries has a wire 16 running from its binding-post 15 to the incandescent lamp 17, arranged on the shelf 5 and provided with a concave reflector 18. This lamp 17 is of any 85 proper candle-power to perform its function hereinafter described.

On the shelf 6 is arranged an electrically-operated switch consisting of a base 19, having a binding-post 20, a bifurcated standard 90 21, in which is pivotally mounted one end of the lever-arm 22, having at or near its central portion the armature 23, arranged directly above and in close proximity to the upper ends of the magnets 24, which are energized from the line-battery 25 through the leading-in wire 26 when the switch 27 is closed by the operator. The free end of the armature has a fixed projecting plate 28 of proper insulating material, on which is mounted 95 a yoke-plate 29, whose lower end is secured to the insulating-plate 28 by means of the pin 30, connected in the lamp-circuit by means of the wire 31 and adapted to be brought into contact with the binding-post 32 on the shelf 100 6, which is connected to one of the batteries 12 by the wire 33, thereby closing the lamp-circuit and energizing the lamp 17. A vertical standard 35 has upon its upper end an overhanging lug 35', adapted to limit the upward movement of the arm 22.

105 To the inner face of the back of the casing

1 is fixed a curved bracket 36, in which is rotatably mounted the horizontal shaft 37, on whose forwardly-projecting end is fixed a semaphore-arm 38 of proper dimensions. On 5 the shaft 37 is fixed an oblique plate 39, one end of which is connected to the shelf 4 by a proper coiled retraction-spring 40. This spring 40 is adapted to normally retain the semaphore-arm 38 in its normal upright position 10 through its connection with the shaft 37, as shown. To the other end of this plate 39 is pivotally connected the upper end of the operating-rod 41, the lower end of which is loosely connected to the top of the plate 29, 15 whereby the vertical movement of the armature will rotate the shaft 37, and thereby actuate the semaphore-arm 38 and brings it to a horizontal position as a day-signal that a train is approaching, while the energized 20 lamp 17 is a night-signal to the same effect.

The operation and manner of employing our invention thus described is briefly stated, as follows: The line-battery 25 and the switch 27 are located in the station office and are connected to our signal apparatus by means of the line-wires 26 and 42, supported in any proper manner, as on poles 43. Our apparatus is placed not only in each station, but at suitable 25 points between stations for the purpose of 30 signaling the engineer of passing trains, as follows: Our apparatus is placed at a proper height upon a suitable support on both sides of the single track in such a manner as to face an approaching train. For example, all 35 the signal apparatus on the right hand of the running train or on the engineer's side face the approaching train and those on the opposite side of the track face in the opposite direction. Each operator controls only those 40 signals upon the left side of the track between his station and the next station in both directions and the corresponding signal apparatus in the office of these stations, whereby when 45 a train leaves a station in either direction the operator by closing the corresponding switch 27 adjusts the said signals to indicate that fact upon each apparatus along the line and also in the station which the outgoing train is approaching simultaneously, the semaphore-arm 50 38 being the signal by day and the lamp 17 by night. Any train which by inadvertence was allowed to pass the last-mentioned station would be notified by one of the said line-signals, and thus effectually blocked against 55 meeting the said approaching train, so that where two trains are approaching each other between stations they will both be blocked or stopped, since each operator will close his switch 27 as the train leaves his station.

60 It is obvious that since in our apparatus the only signals which can be seen by the engineer are those which are intended for him

there can be no confusion of signals. It is obvious that by the use of our invention the engineer who is thus stopped between stations 65 can in like manner by the use of code-signals be instructed to return to his last station or to proceed, or he may be signaled any other desired orders. It is thus seen that by the use of our invention a collision is rendered 70 well-nigh impossible, even where there has been a mistake in train orders.

Having thus described our invention and the manner of employing the same, what we desire to secure by Letters Patent is—

75

1. In an electric signal for railways a line-battery; a signal box or casing; an electrically-operated switch arranged in the said casing and under the control of the station operator; a normally open line-circuit connecting the said switch with the said battery; means for closing the said circuit at pleasure by the station operator; a normally open lamp-circuit in said casing independent of the said line-circuit and adapted to be closed by 80 the said electric switch; a lamp in the said circuit; means in the said box for energizing the said lamp-circuit; and a semaphore-arm pivotally connected to the said electrically-operated switch and adapted to be actuated 85 thereby.

2. An electric signal for railways consisting of a containing-casing; an electrically-operated switch mounted in said casing under the control of the station operator and energized 90 by means of a normally open line-circuit; a semaphore pivotally connected with the said switch, and adapted to be actuated thereby; a normally open lamp-circuit in said casing 95 having an independent source of energy to be 100 closed by the said switch; and a lamp in the said lamp-circuit.

3. The combination in an electric signal for railways of a containing-casing; an electrically-operated switch arranged in the said 105 casing; a normally open line-circuit adapted to energize the said switch; an independent normally open lamp-circuit in the said casing connected to the said switch and adapted to be closed thereby; an incandescent lamp in 110 the said lamp-circuit; a semaphore in said casing pivotally connected with the said switch and adapted to be actuated thereby; and means for returning the said semaphore to its 115 normal position.

Signed by us at Laotto, county of Noble, State of Indiana, this 16th day of June, A. D. 1905.

JOHN B. GORRELL.
